UNITED STATES PATENT OFFICE

WALTER H. ELSEY, OF MARBLE, ARKANSAS

WASHBASIN AND SINK FOR AUTOMOBILES

Application filed December 5, 1929. Serial No. 411,838.

This invention appertains to motor vehicles and more particularly to a novel attachment or accessory therefor.

One of the primary objects of my invention is to provide a novel wash basin associated with a motor vehicle whereby the driver of the vehicle or passengers may conveniently wash their hands before leaving the vehicle when making a call or the like.

Another important object of my invention is the provision of novel means for supporting the wash basin in the motor vehicle whereby the same may be readily and easily moved to an inoperative position out of the way and to an operative position convenient for use.

A further object of my invention is the provision of a novel closure for the bowl which when in its open operative position forms the receptacle for the water and a stop for the drain pipe.

A further object of my invention is the provision of novel means for supplying water to the wash basin, said means embodying a pair of tanks, one of which is preferably arranged in close proximity to the engine and exhaust pipe, whereby the water will be heated and thus allowing the serving of both hot and cold water to the basin.

A further important object of my invention is the provision of novel means for connecting the tank with the wash basin, whereby the wash basin can be readily moved to its operative or inoperative position without disturbing the tank in any way.

A still further object of my invention is to provide an improved wash basin accessory for motor vehicles of the above character, which will be durable and efficient in use, one that will be simple and easy to manufacture, and one which can be placed upon the market and incorporated with a conventional motor vehicle at a small cost.

With these and other objects in view, the invention consists in the novel construction, arrangement and formation of parts, as will be hereinafter more specifically described, claimed, and illustrated in the accompanying drawings, in which drawings:—

Figure 1 is a fragmentary longitudinal section through a motor vehicle showing my im-

proved device incorporated therewith, the device being shown in side elevation.

Figure 2 is an enlarged vertical section through the wash basin per se showing the cover in its closed position.

Figure 3 is a view similar to Figure 2 showing the cover in its open position forming the receptacle for the water, and

Figure 4 is a top plan view of the wash basin with the cover in its open position forming the receptacle for the water.

Referring to the drawings in detail, wherein similar reference characters designate corresponding parts throughout the several views, the letter A generally indicates my improved device and B a motor vehicle with which the same is incorporated.

The motor vehicle B can be of any type or make, such as an automobile bus, touring, sedan or the like, and as shown, the same includes the body 5 having the usual foot board 6, the front dash board 7, and the depending instrument board 8 extending from the cowl 9. Arranged forwardly of the dash board 7 is the usual internal combustion engine 10 having an exhaust pipe 11.

My improved device A comprises a wash basin structure per se 15, which embodies a substantially semi-spherical hollow bottom section or casing 16 having rigidly connected 80 to the lower end thereof and communicating therewith a depending drain pipe 17. A substantially hollow semi-spherical cover or upper section 18 is provided for the lower section or casing 15 and is provided with pivot 85 ears 19 at opposite diametric points for the reception of pivot pins 20 which pivotally connect the said cover to the casing 16. This permits the cover 18 to be swung into the casing 16 to form a bowl or receptacle and 90 to be swung over the casing to form a closure cover therefor. The casing 16 adjacent to its upper edge is provided with an inwardly directed stop lug 21 on which the cover is adapted to rest when the same is in its raised position, as shown in Figures 1 and 2 of the drawings.

To maintain the cover in its raised position I provide a resilient latch 22, which is adapted to engage under the edge of the cover 100

at a point opposite to the lug 21. When it is desired to lower the cover into the casing 16 to form the bowl, the latch 22 is pulled outward and the cover rotated to its lowered position on the pivot 20. It is to be noted that when the cover is in its lowered position that the same overlies the drain pipe 17 and the water flowing into the same is retained therein. As the cover is swung to its raised position the water flows and drains therefrom into the casing 16 and then out the drain pipe. If preferred, the drain pipe can also be provided with a control valve 23.

The basin is adapted to be moved to an inoperative out of the way position of the driver when not in use and is adapted to be pulled outward to a convenient position to be used. To support the basin I provide an extensible bracket 24 of the lazy-tongs type and the inner end of this bracket is bolted or secured by means of a base plate 25 to the dash board 7. The opposite end of the bracket 24 is connected to the drain pipe 17 by the use of a suitable split clamp or the like 26. By this arrangement, it can be seen that the basin can be pushed inward under the instrument board 8 out of the way and substantially out of sight and that when it is desired to use the same the same can be pulled outward to a position to be conveniently reached, as shown in dotted lines in Figure 1 of the drawings.

The casing 16 can be provided with a handle 28 so as to facilitate the moving of the basin to the desired position.

In accordance with my invention I provide a pair of tanks 30 and 31 to act as reservoirs for the water to be used in the basin and the same are connected with the basin in a novel manner as will be later described.

By referring to Figure 1 of the drawings it is to be noted that the tank 30 is of a greater size than the tank 31 and is secured directly over the engine and over the exhaust pipe 11 by means of a clamp 32 whereby the water therein can be maintained at a warm temperature. The tank 31 constitutes a cold water tank and is connected to the tank 30 by means of a supporting bracket 33. Each of the tanks is provided with an enlarged filling neck 34 so that water can be readily placed therein. The tank 30 and the tank 31 is provided respectively with supply pipes 35 and 36 which lead through the dash board 7. These pipes in turn have connected thereto rubber hoses or the like 37 and 38 and these hoses are connected to control valves 39 and 40 communicating with the casing 16 adjacent to the upper edge thereof and above the cover 18 when the same is in its lowered position, whereby the water from the tank will be permitted to readily flow into the bowl formed by the cover. The flow of water through the bowl is of course controlled by the valves 39 and 40.

The drain pipe 17 likewise has connected thereto a hose 42 which is extended to a suitable opening in the floorboard 6 as shown, so as to permit the ready draining of the bowl out of the automobile.

From the foregoing description, it can be seen that I have provided a novel wash basin attachment for motor vehicles which is adapted to be acceptable to the driver of the vehicle due to the fact that the driver's hands generally become soiled through the use of the steering wheel.

Changes in details may be made without departing from the spirit or the scope of this invention.

What I claim as new is:

1. A wash basin comprising a body having a drain pipe communicating with the lower end thereof, water inlet pipes communicating with the body adjacent to the upper end thereof, and a pivoted cover for said body adapted to normally overlie the body and to swing into said body over the drain pipe and below the water inlet pipes to form a bowl.

2. A wash basin comprising a substantially semi-hollow spherical body, a drain pipe for the lower end of the body, water inlet pipes for the upper end of the body, a substantially hollow semi-spherical cover for the body adapted to normally overlie the body, the cover being of a smaller size than the body for swinging movement into the same over the drain pipe and below the water inlet pipes.

3. A wash basin comprising a substantially semi-hollow spherical body, a drain pipe for the lower end of the body, water inlet pipes for the upper end of the body, a substantially hollow semi-spherical cover for the body adapted to normally overlie the body, the covering being of a smaller size than the body for swinging movement into the same over the drain pipe and below the water inlet pipe, and a releasable latch for normally holding the cover in its raised position against swinging movement.

In testimony whereof I affix my signature.

WALTER H. ELSEY.
